UNITED STATES PATENT OFFICE.

PETER L. WILBUR, OF TUCKAHOE, NEW YORK.

DESIGN FOR A FIRE EXTINGUISHER.

Application filed September 16, 1922. Serial No. 3,744. Term of patent 14 years.

To all whom it may concern:

Be it known, that I, PETER L. WILBUR, a citizen of the United States, residing at Tuckahoe, in the county of Westchester and State of New York, have invented a new, original, and ornamental Design for a Fire Extinguisher, of which the following is a specification, reference being had to the accompanying drawing, forming a part thereof, in which—

What I claim is:

The ornamental design for a fire extinguisher as shown.

PETER L. WILBUR.
